UNITED STATES PATENT OFFICE.

HERMAN BURGI, OF SPRINGFIELD, MASSACHUSETTS.

PROCESS OF MAKING GAS.

1,095,806.

Specification of Letters Patent.

Patented May 5, 1914.

Application filed August 26, 1913. Serial No. 786,781.

To all whom it may concern:

Be it known that I, HERMAN BURGI, residing at Springfield, Massachusetts, have invented certain new and useful Improvements in Processes of Making Gas, of which the following is a specification.

This invention relates to improvements in processes for making illuminating gas, and has reference more particularly to what is 10 known as a continuous process wherein coal is continuously fed into the upper end of an externally heated vertical retort and moves downwardly through the retort to the lower end thereof where the residue is withdrawn in the form of coke.

To the continuous processes now in commercial use, the gas is withdrawn from the top of the retort, and as a result some of the hydrocarbons distilled from the coal are not subjected to sufficient heat to permanently fix them, and trouble is experienced at later stages in the process on account of these hydrocarbons condensing and dropping out.

By my improved process, I withdraw all 25 of the gases at a point intermediate the ends of the retort, where the temperature is proper for permanently fixing all of the constituents, with the result that the gas produced is of a much more stable and uniform nature, 30 containing more illuminants and heat units than is possible where gas is taken from the top of the retort.

I am aware that it has been proposed heretofore to separately withdraw the gases produced in the lower and upper parts of the retort and later mix these gases, but this process has not proved a commercial success because the gas produced is not uniform in character. In my process the gases produced in the upper and lower parts of the retort are mingled at the proper zone or level and the strong affinity of the leaner gases, produced in the lower part of the retort for the richer gases causes the product 40 to be uniform and the heat to which the gases are subjected permanently fixes the hydrocarbons without producing free carbon or lamp black.

I have further improved the process by 50 supplying enriching oils to the coal in the zone which is suitable for cracking up and fixing these oils, this zone corresponding substantially with that from which the gases are withdrawn. The oils are conducted 55 through a pipe which is arranged in the mass of coal and extends downwardly from

the top of the retort, the oils being gradually heated as they descend and being readily cracked up when they are introduced into the coal or coke. The ends of these oil supply pipes are so fixed that they terminate in the zone covered by the take-off line but on the opposite side, or removed from the take-off line, so that the broken up oil passes through the heated coal or coke before entering the take-off pipe.

In the accompanying drawing, which is a vertical section of an apparatus for carrying out my process, I have shown two vertical retorts 10 and 11 which are provided at their upper ends with the usual coal feeding apparatus, 12, the latter being of any suitable construction. The lower ends of the retorts are provided with any suitable mechanism, 13, for withdrawing the coke produced. The 70 retorts are surrounded by flame passages, 14, which are supplied from the flue, 15, which receives gas from a producer, 16, the latter being of any suitable type. These flues, 15, feed into the flame passages, 14, around the 80 retorts through openings and are controlled in the usual way by dampers or baffle bricks by means of which the heat is kept constant within certain limits at all points around the retorts, and by which it is possible to 85 maintain the desired temperature in the zone before referred to, where the gas is taken from the retort and where the oils are disintegrated or cracked up and fixed in the 90 gas.

At an intermediate point in the retort 10, is arranged an exit pipe 17, for the gases produced in the retort, this pipe communicating with the retort at a point where the temperature is proper for fixing the gases 95 produced in the upper part of the retort without causing these gases to be burned, and thereby produce free carbon or lamp black. A pipe, 18, may be arranged at substantially the same level as the pipe, 17, and 100 establishes communication between the retorts, 10 and 11, so that the gases produced in the retort 11 may also be withdrawn through the pipe 17, if desired. It will be understood, of course, that a separate exit 105 pipe may be provided for each retort, if preferred.

For the purpose of supplying suitable enriching oils to the coal, in order to improve the illuminating power of the gas produced, 110 I provide a pipe 19, which extends downwardly on the interior of one of the retorts

from the top thereof, to a point where the temperature is proper for cracking up and permanently fixing the gases derived from the enriching oils. This point will usually be substantially in the region or zone of the exit pipe 17, but removed from, or on the opposite side of the retort from the outlet pipe. The pipe 19 is preferably jacketed, as indicated at 20, in order to prevent it from being burned off. The pipe extends through the coal, and oils are fed into the upper end thereof by any suitable means (not shown), and as the oils pass through the pipe they are gradually heated, and when finally introduced into the body of the coal are at the proper temperature for being readily cracked up.

It will be understood that the drawing of the apparatus is more or less diagrammatic and that the proportions indicated are not to be taken as indicative of the proportions which would be used in actual practice, and, therefore, the drawing is to be considered as merely illustrative of the principles of my invention.

In the operation of the apparatus, the gases distilled from the coal in the upper part of the retorts are mingled with the gases produced in the lower part of the retort, and subjected to the heat in the region of the exit pipe 17, which is fixed at some point on the retort where it is possible to maintain a temperature just right for permanently fixing the gases without producing free carbon or lamp black. The pipe 19, for introducing enriching oils may be dispensed with wherever the gas produced from the coal has the requisite illuminating power. As indicated, the outer portion of the moving body of coal in the retort is first distilled and more highly heated than the central portion or crater and the gases which are derived from the central crater are compelled to pass through the more highly heated coal, in order to reach the exit pipe 17, and since the different levels or zones of the retort are maintained at varying temperatures, the gases cannot pass into the exit pipe

17, until they have passed through the zone where the temperature maintained is best suited for fixing the illuminants, light oils, etc., into the gas.

Having thus fully described my invention, what I claim is:

1. The herein described continuous process of making gas which consists in continuously passing coal in a solid body downwardly through an externally heated vertical retort wherein the volatile matters are gradually distilled off and coke produced, and wherein the temperatures at the different levels or zones throughout the vertical column are maintained and so regulated as to produce the desired temperature, bringing the gases produced in all parts of the retort together and withdrawing them from an intermediate zone where the temperature is suitable for fixing the hydrocarbons without producing lamp black.

2. The herein described continuous process of making gas which consists in continuously passing coal in a solid body downwardly through an externally heated vertical retort wherein the volatile matters are gradually distilled off and coke produced, and wherein the temperatures at the different levels or zones throughout the vertical column are maintained and so regulated as to produce the desired temperature, passing suitable enriching hydrocarbons downwardly through the mass of coal from the top of the retort to the zone where the temperature is proper for cracking up and permanently fixing the hydrocarbons and there introducing the hydrocarbons into the coal, and bringing the gases produced in all parts of the retort together in the zone where the enriching hydrocarbons are introduced and withdrawing the gases from this zone.

In testimony whereof I affix my signature in presence of two witnesses.

HERMAN BURGI.
